UNITED STATES PATENT OFFICE.

JOHN W. HORNSEY, OF SUMMIT, NEW JERSEY, ASSIGNOR TO GENERAL REDUCTION GAS AND BY-PRODUCTS COMPANY, A CORPORATION OF DELAWARE.

CHECK-RING FOR ROTARY VESSELS.

1,233,879.

Specification of Letters Patent. Patented July 17, 1917.

Application filed July 15, 1910. Serial No. 572,131.

To all whom it may concern:

Be it known that I, JOHN W. HORNSEY, a citizen of the United States, residing at Summit, Union county, New Jersey, have 5 invented a new and useful Improvement in Check-Rings for Rotary Vessels, of which the following is a specification, reference being had to the accompanying drawings, in which—

10 Figure 1 is a section in perspective of a rotary cylinder equipped with check rings and buckets;

Fig. 2 is a section of Fig. 1 in elevation;

15 Fig. 3 is a detail of a check ring or retarding rib;

Fig. 4 is a detailed plan of Fig. 3 looking from the bottom and showing lock bars in position;

Fig. 5 is a detail of Fig. 2 in elevation;

20 Fig. 6 is a detail of locking means for securing the buckets on line VI—VI of Fig. 5.

Similar letters and figures of reference, refer to similar parts throughout the several views.

25 My invention relates to improvements in check rings for rotary vessels for the treatment of materials, and is designed to treat materials of either gaseous, vaporous, liquid, semi-liquid, or other fluid or solid form, 30 either in contact or out of contact with a treating medium or a chemical reagent.

My invention is of particular value when used with rotary apparatus, since it enables material of any character to be treated by 35 preventing it from flowing too rapidly down the inclined surface of the rotating cylinder, and when used in conjunction with elevating buckets assists in maintaining the material in a finely sub-divided form.

40 I shall herein show and describe my apparatus in the forms which I have found to be preferable for actual use, but it will be understood that many changes may be made, and that the forms here illustrated and described constitute merely preferred embodiments of my invention.

Referring to the drawings, 1 is a section of a cylinder, supported in any suitable fashion so that it can be inclined, and 45 adapted also to be rotated by any suitable mechanism. At suitable intervals along the interior of the cylinder 1 are arranged the

check rings or retarding ribs 2, which consist of annular rings attached to the cylinder in any appropriate fashion, as for instance, by riveting the lugs 32, Figs. 3 and 4, to the inside surface of the cylinder 1. The height and spacing of the ribs or rings 2 may be varied to suit the material being treated, it being apparent that the ribs 2 will be of great advantage in treating liquids in order to prevent the liquid from flowing through the inclined cylinder too rapidly. The ribs also are of advantage in treating solids, in that they prevent more or less globular-shaped pieces from rolling down the inclined longitudinal surface of the cylinder and being discharged with a treated exterior but with an untreated core or center. The ribs 2 tend to prevent this rolling and allow the globular-shaped pieces or lumps to be broken up, and thereby the product of the inclined cylinder is greatly improved both as respects quality and uniformity.

75 The check rings 2 are spaced at any desired interval and may have grooves 3, as shown more particularly in Figs. 3, 4 and 5, on each of their faces in approximately radial directions, though these grooves may be of any shape or direction desired. The longitudinal buckets 4, which are preferably of lesser height than the rings 2, are slid into these grooves 3 and are retained in position by the lock bars 5, Figs. 2, 2 and 6, which are approximately U-shaped in cross-section, as indicated in Fig. 8, and are in the shape of segments of a circle in order that they may be readily removed. At the ends of the lock bars 5 are the keys 6 which are wedge-shaped and are adapted to force the lock bars 5 into position and to secure them. These keys 6 have holes 7 passing through them and are adapted to receive pins 8 which pass also through the check rings 2 and thereby retain the keys 6 and lock bars 5 in position.

It will be noted that there are a number of different grooves 3 (Figs. 3, 4 and 5) on the faces of the check rings 2, which are provided in order to permit the use of buckets of varying inclinations, shapes and capacities so as to adapt them to materials of different consistencies, one type of bucket

being indicated by 4. I may use any equivalent means for attaching the buckets to the check rings; but the particular advantage possessed by the method illustrated, 5 is that it enables buckets of various sizes, shapes, inclinations and capacities to be interchanged with the minimum expenditure of time and labor. The lock bars 5 and keys 6 when used in conjunction with the check 10 rings 2, possess also the further advantage that they force the buckets 4 tightly against the inside wall of the cylinder and thereby prevent the leakage of liquids undergoing treatment, which might otherwise leak down 15 between the outside edges of the buckets 4 and the inside wall of the cylinder without being elevated and redistributed by the buckets in the manner intended. At 4', Fig. 2, I have shown a longitudinal bucket 20 broken away so as to indicate the cross-sectional shape of the same, which will be seen to have a projecting lip 9 in order to retain the material in the buckets 4 while they are being lifted from the lowest to the highest 25 position. These lips 9 and the buckets 4 to which they belong; may be of any desired shape and may vary in different cylinders or in different parts of the same cylinder, as may be best suited to the particular sub- 30 stance which they may be called upon to handle. Obviously the lips 9 may be omitted. It is, however, desirable that the buckets be so shaped and proportioned that they will spill their contents in an approxi- 35 mately steady stream, that is, they should be approximately half full as they pass their highest position, so that half their contents may spill out on either side of the highest position, which will give a sufficiently uni- 40 form distribution for all practical purposes, and, particularly if the buckets between alternate pairs of check rings be staggered as shown in Figs. 3, 4 and 5, will obviate the formation of voids or blank V-shaped 45 spaces through which a treating gas can pass without coming in contact with the shower of material in a thoroughly efficient manner.

The buckets 4 in conjunction with the 50 check rings 2 are also of particular advantage in treating cohesive solids, in that they tend to produce a more even distribution of the material; and when "marbles" tend to form, such agglomerated masses are of 55 smaller size, and as they fall from the buckets to the lower portion of the rotating cylinder, are broken by impingement upon the surface of the cylinder, or upon each other, lose their globular shape and thereaf- 60 ter gradually break up, and the material is, therefore, discharged in a more uniform condition as to quality, dryness, size and temperature than has heretofore been possible.

I have described and shown my improve-

ments attached to an apparatus in the form 65 in which the treating medium is admitted into the cylinder in contact with the material being treated, but it is to be understood that I do not confine myself to the form de- 70 scribed and shown, as this improved check ring or retarding rib may advantageously be applied to any and all forms of rotating apparatus. By the use of my invention materials of widely varying kinds may be ef- 75 fectively treated—such as sugar, starch, salt, milk, coal, lignite, peat, sawdust, petroleum, tannic acid, molasses, ores of various char- 80 acters and many other substances—whether elimination of moisture, concentration, evap- oration, crystallization, fractional or de- 85 structive distillation, purification, physical, mechanical or chemical transformation or change is desired.

My apparatus is also especially adapted 90 for the manufacture, purification or cleansing of illuminating and other gases, with or without the presence of a treating medium, or for the fractional or destructive distillation of materials in the presence of a source of heat out of contact with the material:

What I claim is:

1. In apparatus for treating materials, a 95 rotating vessel, a series of rings arranged transversely to the travel of the material through the vessel, buckets arranged be- 100 tween said rings, the said buckets being re- movably secured to and supported by said rings.

2. In apparatus for treating materials, a 105 rotating vessel, a plurality of rings arranged transversely within said vessel, buckets ex- 110 tending longitudinally in said vessel, said rings being equipped with means for sup- porting the buckets at varying angles.

3. In rotary apparatus for treating ma- 115 terials a series of rings for retarding the travel of a material through said apparatus, and buckets supported by said rings for elevating and redistributing the said material.

4. In apparatus for treating materials a 120 rotating chamber, a plurality of ribs ar- 125 ranged transversely within said chamber, buckets extending longitudinally in said chamber, said ribs having grooved sides adapted to receive and secure the ends of said buckets.

5. In apparatus for treating materials a 125 rotating vessel having therein a chamber for the treatment of materials, a plurality of rings arranged transversely within said chamber, buckets extending longitudinally in said chamber, said rings having grooved sides adapted to receive the ends of said buckets, and locking means secured to said rings whereby the said buckets are secured thereto.

6. In apparatus for treating liquid ma- 130 terials, a rotating vessel in which the liquid

material is to be treated while passing therethrough, retarding means therein comprising ribs arranged transversely to the travel of the material and means for elevating 5 liquid material and distributing it substantially across the cross section of the vessel.

7. In apparatus for treating materials, a rotating vessel, a plurality of material-re-

tarding rings arranged transversely to the travel of the material through the vessel, 10 buckets arranged between the rings of lesser height than the rings.

JOHN W. HORNSEY.
